UNITED STATES PATENT OFFICE.

JOHN D. PEDERSEN, OF JACKSON, WYOMING.

FIREARM.

No. 908,883.

Specification of Letters Patent.

Patented Jan. 5, 1909.

Application filed June 29, 1907. Serial No. 381,445.

To all whom it may concern:

Be it known that I, JOHN D. PEDERSEN, of Jackson, in the county of Uinta and State of Wyoming, have invented certain new and useful Improvements in Firearms; and I do hereby declare that the following is a full, clear, and exact description thereof, which will enable others skilled in the art to which it appertains to make and use the same, reference being had to the accompanying drawings, and to the letters of reference marked thereon, which form part of this specification.

The object of my present invention is to provide an improved fire arm, wherein several advantages of simple breech-up, smooth and easy action, efficient handling of the cartridges and expulsion of the shells, as well as advantages of safety locks and means for releasing the same, easy and simple take-down and other features, are secured with few and simple parts, and which parts are of a design to enable them to be cheaply produced and assembled in the completed gun.

Figure 1 is a general view of the fire arm of my present improved construction. Fig. 2 shows on an enlarged scale a longitudinal section of the frame or receiver and adjacent parts, with the working parts in the position which they assume immediately after firing. Fig. 3 shows a similar longitudinal section with the breech block in open position, and other working parts corresponding. Fig. 4 shows a similar longitudinal section with the breech block in open position, but after the cartridge carrier has operated. Fig. 5 shows in part a longitudinal horizontal section of the frame with a plan view of working parts. Fig. 6 shows a cross section taken on line A—A of Fig. 2 through the frame and mechanism.

Fig. 7 shows a similar section taken on line B—B of Fig. 2. Fig. 8 shows a similar section taken on line C—C of Fig. 3. Fig. 9 shows a longitudinal section of the forward end of the tubular magazine; also including the forward portions of the fire arm and the forward mounting of the magazine. Fig. 10 shows a longitudinal section of the rear end of the magazine, including that part that connects with the breech block in reversed position from Figs. 2, 3 and 4. Figs. 11, 12 and 13 show top, side and end views of the same part. Fig. 14 shows a section on line D—D of Fig. 12, with the bottom view of the parts above the section line and a spring part added. Fig. 15 shows a side elevation

of that part of the frame that is secured to and is detachable and removable with the butt stock of the gun. Fig. 16 is a plan view of the same part. Figs. 17, 18, 19 and 20 are a side elevation, rear end, front end and bottom view respectively of the cartridge carrier. Fig. 21 is a side elevation of the breech block. Figs. 22 and 23 are top and bottom views respectively of the breech block. Figs. 24 and 25 are rear and front end views of the breech block. Figs. 26 and 27 are longitudinal section and a front end view of the barrel part of the receiver or frame. Fig. 28 is a section of the frame taken on line E—E of Fig. 26. Fig. 29 is a section of the frame taken on line F—F of Fig. 26.

Referring to the reference letters and figures in a more particular description, 1 indicates the barrel, 2 the barrel portion of the frame to which the barrel is secured, 3 the stock portion of the frame or receiver and 4 the butt stock. The barrel portion of the receiver 2 consists in the main of side walls 2^a, 2^a and a top 2^b. In addition to this the barrel portion of the frame has a screw-threaded opening 2^c at its forward end to receive the barrel, and another opening 2^d to receive the rear end of the magazine. The stock portion of the frame 3 consists in the main of the trigger plate 3^a, the trigger guard 3^b, the tang 3^c and the end wall 3^d. The two parts of the receiver or frame 2 and 3 together inclose a chamber which contains the major portion of the working parts, chief among which is the breech block 5. At the upper forward end the breech block is provided with an upwardly extending projection providing the locking shoulder 5^a. This shoulder is adapted to engage with the recoil shoulder 5^b of the frame, the same being provided as the rear wall of a recess cut in the top 2^b adjacent to the rear end of the barrel.

For engaging and disengaging the locking shoulder 5^a with the shoulder 5^b and reciprocating the breech bolt in the frame, there is provided beneath the barrel a reciprocating handle or forearm 6, which is attached to and adapted to reciprocate forwardly and rearwardly the tubular magazine 7. The forward end of the magazine is slidingly supported in a loop or holder 8 provided under the barrel and attached thereto, and at its rear end is continued in the bolt operating part 9 which passes into the receiver through the opening 2^d in the forward end thereof.

The magazine tube and the part 9 together constitute the action bar for the breech block. The magazine contains the usual inner tube 10 with follower 11 and spring 12 retained in the magazine tube by a plug 13, which plug, inner tube and attendant parts are adapted to be released to allow the inner tube 10, the spring and follower to be partially withdrawn in order to permit the magazine to be loaded in the usual manner through the opening provided at the point 14.

On the underside, adjacent to the forward end, the breech block 5 is provided with an inclined tooth or projection 5^b, which, when in the closed and breeched-up position, is adapted to rest on the shoulder 9^a provided on the rear end of the part 9, whereby the locking shoulder 5^a is secured in locked position with the frame shoulder s. To depress the forward end of the breech block and disengage the shoulders referred to, the rear end of the part 9 is provided with an inclined projection 9^b adapted to engage with the tooth 5^b of the breech block and draw it downwardly until the tooth 5^b assumes a position in a suitable recess provided for it in the rear end of the operating part 9. When so depressed, the breech block is locked to the rear end of the magazine, serving as an action bar, and is adapted to be reciprocated longitudinally in the frame by moving the handle 6. In its reciprocating movement the breech block is held between the side walls 2^a of the frame, and in the rearward movement is held down and is carried on the rear end of the part 9 by the natural tendency of the tooth 5^b as to its forward end, and at its rear it rides on the top of the vertical flange member 3^a of the frame part 3. In its forward reciprocating movement the breech block is held down against the natural tendency to rise, on account of the inclination of the tooth 5^b, by the top of that part of the block forward of the locking shoulder 5^a sliding along the under face of the top 2^b of the frame until it passes the shoulder s. At the rear the magazine part 9 is provided with shoulders 9^c, 9^d adapted to strike the front end wall of the frame and limit the forward movement of the action bar, and is slotted vertically, as shown at 9^e, to provide a passage for the vertically swinging forward end of the cartridge carrier 15, and forward of the shoulder 9^d, which may be considered the rear end of the magazine opening, is provided on top with a further enlarged slot 9^k affording a passage vertically out of the magazine for the cartridge. The slot 9^e is sufficiently less in width to prevent the cartridge dropping down through the slot 9^e below the plane of the general opening through the tubular magazine. At the rear end of this opening 9^k there are farther cutaway recesses 9°, which afford a passage for the rim of the cartridge head. The front end of the breech

block 5 is provided with a vertical T-slot 5^c with lipped edges to receive the head of the cartridge, and when in its forward and depressed position with reference to the part 9 the vertical slot 5^c in the front end of the breech block is adapted to register with the opening 9^k and the recesses 9° in the rear end of the magazine part 9. The carrier 15 as to its upper edge is in its normal, lower position inclined to the line of movement of the action bar, so that as the action bar is moved rearwardly the rear cartridge in the magazine rides up this incline and is moved partially out of the magazine into the opening 9^k. In connection with the forward movement of the action bar the carrier swinging upwardly from below through the slot 9^c moves the cartridge upwardly from the magazine opening 9^k and up the face of the breech block 5, while the head of the cartridge is retained in the T slot 5^c by the lipped edges thereof.

The carrier 15 is hinged adjacent to its rear end on a hollow pivot 16 supported in the vertical flanges 3^a and 3^b of part 3. On this same pivot is also mounted the hammer 17. The hammer is actuated by a spring 18 coiled around a spindle 19 mounted to slide free through an eye in the frame projection 20 at its rear and provided with a head 19^a at its forward end hinged to the hammer. The spring is interposed between projection 20 and head 19^a. The head by virtue of its vertically swinging movement is adapted, when the hammer falls, to engage and slightly depress the rearward extension 15^a of the carrier which serves to somewhat raise the forward end of the carrier and more particularly serves to release the action lock, which will be described later.

The hammer is provided with the usual catch shoulder adapted to be engaged by the trigger 21 and hold the hammer in cocked position prior to being released by the operator. The trigger is pivoted at 21^a. The hammer is adapted to strike the firing pin 22, which extends from rear to front of the breech block, and is located in a slot 22^a in the side of the block. The firing pin is retracted by a spring 23 located in a slot in the body thereof and interposed between the rear end of the slot and a pin 24 in the block, passing through the slot. The extractor 25 is a spring actuated hook mounted in a recess 25^a at the side of the breech block. The hook of the extractor provides in part one of the walls of the T slot in the face of the breech block up which the head of the cartridge passes. Opposite the extractor the slot is reduced to a bevel or undercut, as shown by dotted lines at 26, and from which the cartridge head may be displaced by application of sufficient force as hereinafter explained.

For actuating the carrier, there is pro-

vided on the part 9^a a carrier dog 27 controlled by a spring 27^a which allows it to retire during a certain portion of the operation. At the time when the action bar is at or near the limit of its rear movement, the carrier dog 27 engages in the rear part of the angular slot 15^b in the side of the carrier. As the breech block is moved toward the closed position travelling with the action bar, the cartridge carrier is operated to move the cartridge vertically out of the magazine and up the face of the breech block with its head running and held in the T slot 5^c. This movement of the carrier is caused by the angular position of the slot 15^b while the dog 27 engaging therein moves in a straight line. At the upper end of the slot 5^c the cartridge head is forced in between the spring extractor 25 and the continuation of the opposite wall of the slot, where it is pinched and held against any tendency to slide down the slot when the carrier retires. To provide against any tendency to force the cartridge out of the top of the slot 5^c incident to the operation of the carrier or otherwise, there is provided at a suitable point the undercut shoulder 28. The arrangement is such as to hold the cartridge projecting from the front end of the breech block in line with and so as to enter the bore of the barrel (as shown in Fig. 4) as the breech block is closed.

The carrier is returned to its normal lower position after the dog has passed out of the cam slot 15^b and beyond the end of the carrier by the spring 29 interposed between the part 15^a of the carrier and the trigger and serving to operate both. In order to cause the dog 27 to spring outwardly and slide over the side of the carrier to reach the rear of the cam slot 15^b, there is provided in the front end of the carrier a cut 15^c, having an inclined bottom, up which the dog rides as the action bar is moved towards its rear position. But the cut 15^c does not normally register with the dog 27. It normally takes a position somewhat below, so that the dog will strike against the front end of the carrier thereby locking the action bar while the gun is in firing position. The downwardly swinging movement of the forward end of the carrier is stopped at a suitable point to accomplish the above stated purpose by having an inclined shoulder, as shown, striking a spring supported stop pin 30 provided in a socket in the forward end of frame part 3^a. When the hammer falls the part 19^a engaging with the rear portion 15^a of the carrier causes the forward end of the carrier to raise sufficiently to let the dog 27 enter the cut 15^c, thus automatically releasing the action lock. This lock can also be manually released by the operator raising the front end of the carrier. To facilitate the operator raising the front end of the carrier, there is provided in the underside of the frame part

3^a a recess 31, which enables the carrier to be readily reached for manual operation. The position of the carrier, particularly when its lower edge is exposed at the recess 31, serves as an indicator as to the position of the hammer, and incidentally whether the action is locked or not.

The firing pin in addition to its usual function of exploding the cartridge serves the additional function of an ejector. To this end it is somewhat extended beyond the breech block at its rear end and arranged to strike the rear wall 3^d of the frame (see Fig. 3) just before the breech block reaches the limit of its rearward movement. This serves to project the forward end of the firing pin from the breech block, to forcibly disengage the cartridge head from the undercut at 26 and expel the shell through the ejection opening 32 in the right-hand side of the frame with a whirling, end over end, movement caused by the opposite side of the head being held by the extractor 25, temporarily.

The carrier is provided with an arm affording two stop shoulders 15^d and 15^e adapted to engage with and lock the operation of the trigger when the carrier is in certain position, and with an intermediate recess to receive a protuberance on the trigger and permitting the movement of the trigger when the carrier is in its normal position. When the carrier at its forward end is raised the shoulder 15^d swings into a position to block the operation of the trigger, providing a safety lock against accidental (or otherwise) operation of the trigger before the gun is breeched up and in firing condition. To this end the length of the cam slot 15^b and the lower edge of the carrier which rides on the dog 27 is made of proper length to allow the carrier to drop off or become released, substantially at the point that the action bar completes its forward movement. When the carrier is released by the action bar it moves to its normal lower position against the stop 30 under the influence of spring 29, in which normal position the protuberance on the trigger registers with the recess between the shoulders 15^d and 15^e and the trigger is free to be operated.

The carrier may be moved to a position below its normal position, being forced past the spring supported stop 30 by the operator. To facilitate the operation of the carrier into and out of this position the carrier is provided with a downwardly extending projection 15^f, which is preferably knurled on the front and rear and occupies a position in a slot in the front bow of the trigger guard. When in its lowest possible position the shoulder 15^e of the carrier blocks the movement of the trigger. The carrier also blocks the movement of the forearm and action bar and other working parts and the gun can not be fired or operated in any way until the for-

ward end of the carrier is moved up slightly. The spring supporting the carrier stop 30, together with the inclines of the shoulders of the carrier which engage this stop, allow the carrier to be forced by the stop in either direction by the application of sufficient force. When in its lowest possible position the carrier indicates the fact that the trigger and mechanism is completely locked.

10 The frame part 3 fits into the frame part 2 and the part 3 is provided at its forward end with a tenon 3^a adapted to engage in a suitable recess 2^b in the part 2, and the frame parts are secured together by a thumb screw bolt 40 engaging in suitable openings in the plates 2^a and passing through the tubular pivot 16. When the bolt 40 is removed the frame parts can be readily separated, exposing the mechanism for examination and cleaning, or for ready removal as to the main parts. When the parts of the arm are taken apart, as above suggested, the breech block may be moved rearwardly by the action bar to such an extent as to allow the projection 25 on top of the block which carries the breech-up shoulder 5^a to enter the recess 2^b in the top plate of the frame. When so positioned, the block may be raised sufficiently to disengage it from the action bar and the action bar moved forwardly out of the way and the block removed. In assembling the parts the reverse of this operation, of course, is pursued.

It will be noted that the fire arm is adapted to handle various lengths of cartridges promiscuously, and that no device for stopping and sorting the cartridges as they discharge from the magazine is required. Further, it will be noted that the reciprocal 40 movement of the tubular magazine when serving as an action bar tends to jar and stir the cartridges in such a way as to obviate any tendency to stick or jam in the magazine, more particularly incident to dirt or grease adhering to the walls of the magazine.

It is evident that numerous changes and modifications in and from the construction herein described may be made without departing from the spirit of my invention.

50 What I claim as new and desire to secure by Letters Patent is:

1. In a fire arm, the combination of a reciprocating breech block having an inclined tooth and mounted in the frame to slide longitudinally and having a rising and falling movement at one end, of an action bar mounted for longitudinal movement and having a recess to receive the tooth of the breech block and a shoulder to support the breech block in breeched-up position, substantially as set forth.

2. In a fire arm, the combination of a barrel and frame, having a recoil shoulder adjacent to the end of the barrel, a reciprocating breech block having a locking shoulder

on top adjacent to the forward end and an inclined tooth, an action bar having a recess to receive the tooth, and a shoulder to support the breech block in closed and locked position, substantially as set forth. 70

3. In a fire arm, the combination of a longitudinally and vertically movable breech block, a cartridge carrier and an action bar coupled to the block and arranged to operate same longitudinally and vertically, and 75 coupled to the carrier and arranged to operate the carrier, substantially as set forth.

4. In a fire arm the combination of a reciprocating breech block, a sliding action bar coupled to the breech block, a cartridge carrier which is also an action bar lock and means to actuate the said carrier-lock, substantially as set forth. 80

5. In a fire arm, the combination of a breech block, an action bar coupled to and 85 arranged to operate the block, a cartridge carrier mounted on a fixed pivot and arranged to swing at its forward end to lock the action bar, substantially as set forth.

6. In a fire arm, the combination of a 90 breech block, an action bar coupled to the block, the carrier mounted on a fixed pivot and arranged to lock the action bar, and a hammer adapted to engage the carrier and release the lock, substantially as set forth. 95

7. In a fire arm the combination of a sliding breech block, a sliding action bar, a hammer, a trigger and a cartridge carrier which is also a trigger lock and action bar lock, and means for operating the carrier-lock, substantially as set forth. 100

8. The combination in a fire arm of a breech block, a trigger, a hammer and a movable cartridge carrier having means to engage and lock the trigger in the two extreme 105 positions of its movement, substantially as set forth.

9. In a fire arm the combination of a vertical and longitudinal movable breech block, a longitudinal movable magazine connected to 110 the breech block to operate the breech block vertically and longitudinally, the magazine having a passage for the discharge of cartridges vertically, the breech block having a slotted face to receive the cartridge head from the magazine and hold and control the cartridge and the cartridge carrier, substantially as set forth.

10. The combination in a fire arm of a breech block, a trigger, a hammer and a 120 movable cartridge carrier having means to engage and lock the trigger, mechanism to engage and operate the carrier in transferring cartridges and become disengaged from the carrier to permit it to be manually operated 125 to the trigger locking position, substantially as set forth.

11. In a fire arm the combination of a breech block, an action bar for operating the breech block, a hammer, a trigger and a car

tridge carrier having means to engage and lock the trigger and engage and lock the action bar, substantially as set forth.

12. In a fire arm the combination of a breech block, an action bar for operating the breech block, a hammer, a trigger and a cartridge carrier having means to engage and lock the action bar, substantially as set forth. 5

13. In a fire arm the combination of a breech block, an action bar connected to the breech block, a hammer, a hammer spring and a cartridge carrier, means to connect the hammer spring to the carrier to move the same, means to connect the action bar to 10 the carrier to move the same and means to lock the action bar by the carrier, substantially as set forth. 15

14. The combination in a fire arm of a separable frame providing a chamber for the operative parts, a breech-block inclosed within the frame and reciprocally movable therein, an action bar with which the breech block is held engaged by the top wall of the frame, a clearance in the top wall for the breech block at a point to the rear of the 20 normal rear position of the breech block available when the frame is separated to permit the disengagement of the breech block from the action bar, substantially as 25 set forth. 30

15. In a fire arm the combination of a breech block, an action bar connected to the breech block, a hammer, a hammer spring, a cartridge carrier having means for engaging and locking the action bar and means for engaging and locking the trigger, means to operate the carrier from the hammer spring and means to connect the action bar to the carrier to move the same, substantially as 35 set forth. 40

16. In a fire arm the combination of a breech block mounted in the frame for vertical and longitudinal movement, a longitudinal movable tubular magazine connected to the breech block by means affording a limited 45 independent movement of the magazine with reference to the breech block and to operate to produce a vertical movement of the breech block, the magazine having a discharge 50 opening to move into registering position with the front of the breech block, substantially as set forth.

In witness whereof, I have affixed my signature, in presence of two witnesses, this 24th day of June 1907.
